PLUG FUSE RECEPTACLE STRUCTURE

Edwin W. Landmeier, Cincinnati, Ohio, assignor
to The Wadsworth Electric Manufacturing Co.,
Inc., Covington, Ky., a corporation of Ken-
tucky

Application August 4, 1941, Serial No. 465,329

6 Claims. (Cl. 200—133)

This invention relates to receptacles for plug type fuses and it is directed particularly to an improved structure in which the respective parts remain in rigid assembly throughout prolonged usage of the apparatus.

The conventional plug fuse is made up of a body having a peripheral contact band with screw threads on its surface adapting it to be screwed into the shell of a fuse receptacle. A center contact is provided at the bottom of the plug fuse for engagement with a center contact in the fuse receptacle. The center and peripheral contacts of both the plug fuse and the fuse receptacle are insulated from one another by means of an insulating washer disposed intermediate the center contact and the bottom wall of the fuse shell.

The present invention is directed particularly to fuse receptacles in which the center contact is a headed screw or bolt, the head portion serving as the contact button for engagement with the bottom contact of the fuse plug, while the threaded shank serves as a fastener for clamping the receptacle assembly in position to a base block member or the like. This type of structure is desirable in that it may be assembled quickly with a screw driver or wrench, and may be disassembled with equal ease; whereas, riveting or the like requires special equipment and makes replacement of a worn or burned part difficult. Moreover, the use of a headed screw is desirable in that it permits adjustments to be made, as in switch structures where contact members which must reside in predetermined spaced relationship are in direct electrical connection with the shell or center contact members of the fuse assemblies and held so by the screw.

However, when a plug fuse is screwed into a receptacle of this type, the center contact of the fuse presses upon the center contact of the receptacle and the frictional engagement of these contacts, one with the other, causes an unscrewing action to be exerted upon the center contact screw of the receptacle assembly each time a fuse plug is removed for replacement purposes. It frequently happens that after several replacements, the center contact screw of the assembly becomes appreciably unloosened and the parts, being no longer clamped together by the screw, are free to move about to such a degree that short circuiting takes place.

The principal object of the present invention has been to provide a structure in which the center contact screw is locked frictionally or held

against rotation with respect to the shell so as to withstand any loosening action imposed on it when a fuse plug is removed.

These results, briefly, in the preferred structures of the present invention, are accomplished by providing in the fuse shell an insulating washer which is arranged so as to be nonrotatable with respect to the fuse shell and by seating the head of the center contact screw upon a friction member or lock washer element supported by the insulating member. In this manner the screw is restrained against movement relative to the insulating washer and the latter, in turn, is restrained against movement relative to the fuse shell.

In the preferred embodiment the insulating washer has a tail portion which extends through an opening cut in the fuse shell wall; for instance, the tail portion may extend through the opening provided in a conventional fuse shell for reception of a terminal connector. The friction member in the preferred embodiment is in the form of a double lock washer configurated at its one face for frictional engagement with the insulating washer and at its other face for frictional engagement with the underneath surface of the screw head.

The present application is directed both to the improved lock washer and the improved insulating washer, that is, the lock washer may be used with an insulating washer of the conventional circular type or the improved insulating washer can be used without the lock washer. However, each complements the other and best results are obtained when both are used.

In the drawing, which discloses preferred embodiments of the invention,

Figure 1 is a cross-sectional view showing a fuse receptacle constructed in accordance with the present invention.

Figure 2 is a sectional view taken on the line 2—2 of Figure 1.

Figure 3 is a perspective view of an insulating washer embodying the present invention.

Figure 4 is a perspective view of a lock washer made in accordance with the invention.

Figure 5 is a perspective view showing a modified form of the lock washer.

The base to which the fuse receptacle is attached may be of the conventional form, as illustrated for example in Figure 1, of a block of insulating material 1 configurated so as to provide a cavity 2 within which the fuse shell 3 may be disposed with its bottom wall 4 resting on the bottom wall 5 of the cavity 2. The fuse

shell is of the conventional type, its periphery having threads 6 formed in it for reception of the threads formed on the body of a plug fuse. An opening 7 is cut through the side wall of the shell 3 just above its bottom wall so that terminal connector 8 may pass through the opening and rest in electrical contact with the bottom wall of the fuse shell. The terminal extends beyond the cavity 2 and carries a screw terminal 9 to which a conductor may be attached. The central portion of the terminal 8 which resides within the fuse shell preferably is of circular contour so that it engages the bottom of the shell over a substantial area and at its central portion it has a clearance opening 10. If desirable a slot 11 may extend from the clearance opening 10 to the edge of the connector opposite the screw terminal 9 and within the fuse receptacle making it of fork formation for ease of assembly. The portion 12 of the connector which extends beyond the fuse shell to the terminal 9 outside the fuse cavity is relatively narrow.

The insulating washer 13 rests over the central portion of the connector 8 within the shell and it, likewise, preferably is of circular contour, being of such diameter that its periphery overhangs the periphery of the central portion of the connector 8 so as to conceal it. However, the insulating washer in the structure shown is provided with a tail 14 which projects through the clearance opening 7 of the fuse shell, thereby preventing the insulating washer from being rotated relative to the shell. The insulating washer 13 is preferably made of insulation board or fiber board of suitable thickness and it is provided with an opening 15 at its center.

Connector screw 16 has a head 17 which forms the center contact of the fuse receptacle assembly. The shank of the screw 16 extends through the respective openings 12 and 15 in the connector and insulating washer, down through the base of the plug 1, and into threaded engagement with a connector 19. It will be seen that screw 17 serves to fasten all of the parts into a rigid assembly, pulling the bottom wall of the fuse shell and the terminal connector 19 together against the opposite faces of the base plug 1. Connector 19 may extend into connection with the switch member in composite switch fuse units or may terminate in a screw connector 20 to receive the other electrical conductor of a pair.

In the preferred embodiment of the present invention lock washer 21 is disposed intermediate the underneath surface of the head of the screw 16 and the insulating washer 13. The lock washer has one or a plurality of tangs 22 at a point preferably adjacent its periphery which extend downwardly. Under the pressure exerted upon them by the screw head, these tangs tend to bite into the insulating washer, though it is to be noted that they are sufficiently blunt or yieldable that they do not bite through it. One or a series of tangs 23 extend from the opposite face of the lock washer at a point adjacent its central opening so that they may be engaged by the underneath surface of the screw head in order to increase its frictional contact with the lock washer to prevent backward rotation of the screw. In the preferred structure the lock washer is of sufficiently large diameter to reside over a substantial portion of the insulating washer area. This arrangement avoids localization of pressure at the central portion of the insulating washer

and thereby prevents the insulating washer from tending to warp.

In the form shown in Figure 4, the tangs 22 are blunt bosses extending in a generally radial direction at the periphery of the lock washer. In cross section these tangs may be of V shape or rectangular in cross section so that when the lock washer is pressed against the insulating washer there is considerable pressure at the local area of the tangs against the lock washer to prevent its rotation. The tangs 23 struck from the washer and extending in a clockwise direction provide edges 24 which bite into the metal of the screw head to prevent rotation of it in screw loosening direction.

The modified form of lock washer shown in Figure 5 has U-shaped tangs 25 which are of a resilient nature; the U-shaped tangs extend downwardly at an angle in a counterclockwise direction providing edges positioned so as to press upon the insulating washer and prevent the lock washer from being rotated in a counterclockwise direction. These tangs instead of being located at the periphery are disposed in the body of the washer and are of a yieldable nature so that if subjected to extreme pressure they tend to become bent back up into the body of the washer. Thus, their form is such that they cannot bite through a fiber board or similar substance of which the insulating washer may be comprised.

As previously indicated, the structure of the insulating washer 13 is of such a nature that it is held in non-rotatable position with respect to the fuse shell and, consequently the frictional engagement is substantial. The lock washers 35 may be omitted in instances where the likelihood of fuse replacement is not great and where it is desired to minimize the cost. Also, omitting the lock washer element, the underneath surface of the screw head may be serrated to increase its frictional engagement with the insulating washer. In either instance, and to the greatest degree in the preferred embodiment, as disclosed in the drawing, all of the parts are held against movement relative to one another so that repeated removal of the plug fuses does not disturb the firmness with which the parts are assembled or permit the center contact to become loosened.

This application is a continuation in part of my copending application Serial No. 403,289, filed July 21, 1941, for Switch structure.

Having described my invention, I claim:

1. A receptacle for a plug fuse comprising a shell, a headed contact member disposed within the shell, an insulating member positioned intermediate the head of the contact member and the shell to insulate the same from one another, mutually engaging means for holding the insulating member and shell in non-rotatable relationship, and a friction member disposed intermediate the insulating member and the head of the contact member, said friction member having means at its one face for frictionally engaging the surface of the insulating member and having means at its other face for frictionally engaging the underneath surface of the contact member head.

2. A fuse receptacle assembly comprising a fuse receptacle shell, a center contact member disposed within the shell and a washer member positioned intermediate the contact member and the shell, the said shell having an opening therein, the said washer member having a portion extending through the shell opening whereby the washer member is held in non-rotatable relation-

ship with respect to the shell, and friction means intermediate the washer and the center contact member for restraining the contact member against rotation relative to the washer.

3. A fuse receptacle assembly comprising a fuse receptacle shell, a headed contact member having a threaded shank extending through the bottom of the shell and the said shank constituting a screw for fastening the assembly in position, an insulating washer disposed intermediate the head of the contact member and the shell, and a lock washer having tang means struck from its one face to bite into the surface of the insulating washer and having tang means extending from its opposite surface for frictional engagement with the screw head.

4. The combination with a receptacle configured for reception of a plug-type fuse and constituting a contact for the peripheral contact thereof, and a headed fastener member residing within said receptacle and constituting an electrical contact for engagement with the bottom contact of a plug fuse, of a washer constructed of insulating material interposed between the fuse receptacle and the head of the fastener member to insulate the same from one another, and a lock washer interposed between the insulating washer and the head of said fastening member, said lock washer having tang means extending from its one face adapted to bite into the insulating washer and having other tang means extending from its other face to bite into the headed portion of the fastening member.

5. The combination comprising a receptacle

configured for reception of a plug-type fuse and constituting a contact for the peripheral contact thereof, and a headed fastener member residing within said receptacle and constituting an electrical contact for engagement with the bottom contact of a plug fuse, of a washer constructed of insulating material interposed between the fuse shell and the head of the fastener member to insulate one from the other, and a lock

10 washer interposed between the insulating washer and the head of said fastening member, said washer including means for holding the same in non-rotatable relationship with respect to said shell.

15 6. The combination comprising a receptacle configured for reception of a plug-type fuse and constituting a contact for the peripheral contact thereof, and a headed fastener member residing within said receptacle and constituting an elec-

20 trical contact for engagement with the bottom contact of a plug fuse, of a washer constructed of insulating material interposed between the fuse shell and the head of the fastener member to insulate the same from one another, and a lock

25 washer interposed between the insulating washer and the head of said fastening member, said insulating washer including means for holding it in non-rotatable relationship with respect to said shell, said lock washer having tang means ex-

30 tends from its one face adapted to bite into the insulating washer and having other tang means extending from its other face to bite into the headed portion of the fastening member.
